UNITED STATES PATENT OFFICE

109,865

DESIGN FOR A SHOE

Charles H. Caldwell, Brockton, Mass., assignor to
Geo. E. Keith Company, Campello, Mass., a
corporation of Massachusetts

Application December 28, 1937, Serial No. 73,898

Term of patent 3½ years

To all whom it may concern:

Be it known that I, Charles H. Caldwell, a citizen of the United States, residing at Brockton, in the county of Plymouth and State of Massachusetts, have invented a new, original, and ornamental Design for a Shoe, of which the following is a specification, reference being had to the accompanying drawing, forming part thereof.

In the drawing:

Figure 1 is a top plan of a shoe showing my new design; and

Figure 2 is a side elevation of the same.

Both sides of the shoe present substantially the same appearance.

The essential feature of the invention resides

in the arrangement of perforations in the material of the shoe upper, wherein the tip and the quarters of the shoe are decorated with perforations which are prominent by reason of the large size of some of their holes; and a large area of quiet aspect of vamp intervenes between the tip and the quarters. As the design is applicable to shoes of various shapes and styles the representation of shoe is merely conventional, for showing an application of the design.

I claim:

The ornamental design for a shoe, as shown and described.

CHARLES H. CALDWELL.
